(57) **CLAIM**

We claim the ornamental Design for a fork body, as shown and described.

DESCRIPTION

FIG. 1 is a perspective view of a fork body;

FIG. 2 is a top plan view of the fork of FIG. 1;

FIG. 3 is a side elevation view of the fork of FIG. 1, with an opposite view being identical thereto;

FIG. 4 is a front elevation view of the fork of FIG. 1;

FIG. 5 is a rear elevation view of the fork of FIG. 1; and,

FIG. 6 is a bottom plan view of the fork of FIG. 1.

The broken lines shown in FIGS. 1-6 are for illustrative purposes only and form no part of the claimed design.
